HIGH-VOLTAGE DISCHARGE TUBE

Albert Bouwers, Eindhoven, Netherlands, assignor to N. V. Philips' Gloeilampenfabrieken, Eindhoven, Netherlands

Application November 23, 1937, Serial No. 176,102
In Germany December 16, 1936

8 Claims. (Cl. 250—146)

My invention relates to high-voltage discharge tubes, and more particularly to an envelope construction for such tubes.

As my invention is particularly advantageous for use in X-ray tubes, I shall describe the same in this connection. However, it is not limited thereto but is equally applicable to other types of high-voltage tubes, such as rectifiers and corpuscular ray tubes.

10 Discharge tubes for very high voltages, i. e. voltages of the order of 200 kilo volts and higher, must have insulating envelope portions of large size. This increases the size of the tubes and makes them relatively fragile and subject to 15 breakage, and as they are comparatively costly, this is a serious disadvantage. Furthermore, the portability of the tubes, which is particularly important in the case of irradiation tubes, is obviously greatly impaired by their large size.

20 The main object of my invention is to overcome the above difficulty, and to provide high-voltage discharge tubes of small size and of strong construction.

In accordance with the invention I provide, at 25 least at one end of the tube, an outwardly-open fold in the insulation part of the tube envelope. This fold, which is of annular shape, surrounds the tube axis, and extends into the vacuum space of the tube while remaining at a considerable distance from the voltage drop space between the 30 high-voltage electrodes. The space formed by the fold is preferably filled with a solid insulation. The insulating capacity of this space should not be decreased by conductive inserts.

35 The invention is particularly advantageous with a discharge tube whose wall comprises in known manner a central portion which has the same potential throughout during operation of the tube. Such a portion, which hereinafter and 40 in the claims will be designated as an equipotential portion, may be formed by a metal ring to whose edges the insulating parts that withstand the potential differences between the electrodes are sealed, or it may be constituted by metal coatings which electrostatically screen a portion of the glass wall, so that this portion will have a 45 uniform potential throughout.

The use of such an equipotential portion ensures that there will be a stable distribution of 50 the dielectric load over the insulating wall parts, and thus allows these parts to be made for a voltage which corresponds to this distribution and is generally lower than the voltage otherwise to be taken into account. I have found that in this 55 case the use of folds arranged according to the

invention results in a much greater decrease in the tube length than with tubes having no equipotential wall portion.

In constructions in which an electrode is supported from the insulating envelope portion by a seal of large surface, for instance by a metal disc fused into the insulating portion, and in which there is danger of the seal being damaged by thermal conduction or dissipation of heat from an active part of the electrode, I arrange the 5 seal near the end of the tube and thus as far as possible from the point at which the heat is generated. In prior tubes, such sealing of the electrodes to the tube wall would cause a considerable 10 reduction in length of the insulating portion. In 15 tubes according to the invention, however, the entire insulating length measured along both sides of the fold is effective as a leakage path between the seal and the periphery of the insulating portion. 20

In order that my invention may be clearly understood and readily carried into effect, I shall describe the same in more detail with reference to the accompanying drawing in which,

Figure 1 is a sectionized view of an X-ray tube 25 embodying the invention and

Fig. 2 is a sectionized view of a portion of an X-ray tube illustrating another embodiment of the invention.

The X-ray tube shown in Fig. 1 has an envelope 30 comprising an equipotential portion in the form of a metal ring 1, for instance of ferro-chrome, to the ends of which are sealed insulating portions 2 and 3 of glass. Portions 2 and 3 are provided with folds 4 and 5 respectively which are 35 open to the outside of the tube. The folds extend into the vacuum of the tube but are spaced a considerable distance from the voltage-drop space between the electrodes. Because of this the projecting edge of the folds will remain free from 40 dangerous electric charges.

Glass portion 3 extends to form a reentrant part 15 to the end of which is sealed a cathode structure 7 projecting beyond the fold 5 within which is disposed an incandescent filament 20 45 provided with supply leads 16—17. It will be noted that portion 3 has an insulation length between ring 1 and cathode structure 7 of more than three times its overall length in the direction of the axis of the tube. 50

Glass portion 2 differs from portion 3 in that it does not form a reentrant part, but a disc 11, for instance of chrome-iron, is sealed at 21 to the edges of fold 4. A metal rod 10 is secured to the inner surface of disc 11. This rod projects be- 55

yond the fold 4 and carries on its lower end a target 9 in the form of a disc of refractory material, such as tungsten, which is inclined to cause the X-ray beam to pass through a glass window 5 8 sealed in ring 1. A metal rod 18 secured to the outer surface of disc 11 serves as a terminal for the anode.

As the seal 21 is located at the end of the tube it will not be intensively heated by the dissipation 10 of heat from disc 9, which is heated to a high temperature during the operation of the tube. However, because of fold 4 the insulation length of portion 2 will still be more than twice the overall length of portion 2 along the axis of the 15 tube.

With the construction illustrated, X-ray tubes for operation on voltages above 300 kv. can be made with an overall axial length of less than 30 cms.

20 If the anode is of the cooled type, it is unnecessary that the seal between the anode body and the insulating portion be located at the extreme end of the tube and thus portion 2 of Fig. 1 may be formed with a reentrant part. Such a construction is illustrated in Fig. 2, in which the insulating portion 23 is similar in shape to portion 3 of Fig. 1. Sealed to the lower end of the reentrant part of portion 23 is a ring 24 of ferro-chrome secured to an anode body 25, for instance 25 of copper. Anode body 25 carries a target 26 of refractory material such as tungsten and the cooling of the anode is effected by means of a heat absorbing and radiating body 31 whose end fits into a cavity of body 25.

30 Referring now to Fig. 1 members 27 and 28 of solid insulating material such as "Bakelite" have portions 12 and 13, respectively, extending into folds 5 and 4 respectively. Portions 12 and 13 prevent a disruptive discharge occurring between the opposing walls of the folds, which are at a high potential difference during operation 35 and are not separated by a vacuum space.

Member 27 has a central projecting portion 14 which extends into the space formed within re- 40 entrant part 15 and surrounds leads 16 and 17. Portion 14 serves to prevent disruptive discharges in the space between the surface of reentrant part 15 and leads 16 and 17.

To prevent as far as possible the occurrence of 45 any harmful ionization in the air spaces, which are unavoidably present between the solid members 27 and 28 and the glass portions 3 and 4, between projecting part 14 and lead wires 16-17, or between member 28 and rod 18, I prefer to fill 50 these spaces with an insulating cement 38. For this purpose I prefer to use a hardening non-shrinking insulating material such as litharge.

It should be noted that in constructions according 55 to the invention it is essential that the space within the fold, i. e. the space occupied by portions 12 and 13 in Fig. 1, is surrounded by a vacuum space. In Fig. 1 an annular vacuum space is formed by the outer tube wall and the outer side of the fold. Because of this a perfect 60 insulation will be obtained as the leakage path from the lower edge of fold 4 to the outer wall 2 is considerably lengthened.

While I have described my invention in connection 65 with specific examples and applications, I do not wish to be limited thereto, but desire the appended claims to be construed as broadly as possible in view of the prior art.

What I claim is:

1. A high-voltage discharge tube comprising an 70 envelope having an insulating portion forming at

one end of the tube an annular fold surrounding the axis of the tube and open toward the outside of the tube, and electrodes within said envelope and spaced apart to form a voltage-drop space, said fold extending into the vacuum space of the 5 tube and being spaced a considerable distance from the voltage-drop space, and non-ionizable insulating material completely filling the space within the fold.

2. A high-voltage discharge tube comprising an 10 envelope having an equipotential portion and an insulating portion sealed thereto, said latter portion forming at one end of the tube an annular fold surrounding the axis of the tube and open toward the outside of the tube, and electrodes 15 within said envelope including an electrode carried by said insulating portion, said electrodes being spaced apart to form a voltage-drop space, said fold extending into the vacuum space of the tube and being spaced a considerable distance 20 from the voltage-drop space, and non-ionizable insulating material completely filling the space within the fold.

3. A high-voltage discharge tube comprising an 25 envelope having an insulating portion forming at one end of the tube an annular fold open toward the outside of the tube, electrodes within said envelope including an electrode carried by said insulating portion, said electrodes being spaced apart to form a voltage-drop space, said fold extending into the vacuum space of the tube, and non-ionizable 30 insulating material completely filling the space within the fold.

4. A high-voltage discharge tube comprising an 35 envelope having an insulating portion forming at one end of the tube an annular fold open toward the outside of the tube, electrodes within said envelope including an electrode carried by said insulating portion, said electrodes being spaced apart to form a voltage-drop space, said fold extending into the vacuum space of the tube and a member of solid insulating material extending within the fold and forming spaces with the surface thereof, and a non-ionizable material completely filling said latter spaces.

5. A high-voltage discharge tube comprising an 40 envelope having an insulating portion forming at one end of the tube an annular fold surrounding the axis of the tube and open toward the outside of the tube, and a reentrant portion surrounded by said fold, and electrodes within said envelope including an electrode carried by said reentrant portion, said electrodes being spaced apart to form a voltage-drop space, said fold extending into the vacuum space of the tube and being spaced a considerable distance from the voltage-drop space, and a non-ionizable insulating material completely filling the space within said fold.

6. A high-voltage discharge tube comprising an 45 envelope having an insulating portion forming at one end of the tube an annular fold surrounding the axis of the tube and open toward the outside of the tube, electrodes within said envelope including an electrode carried by said insulating portion, said electrodes being spaced apart to form a voltage-drop space, said fold extending into the vacuum space of the tube and being outside the voltage-drop space, a member of solid insulating material within said fold and forming thin interspaces with the surface thereof, and insulating cementing material filling said interspaces.

7. A high-voltage X-ray tube comprising an 50 envelope having two end portions of insulating

material, an anode and a cathode each carried by one of said portions and spaced apart to form a voltage-drop space, each of said end portions having an annular fold surrounding the axis of the tube and extending into the vacuum space of the tube, said anode and cathode extending each beyond the fold of that portion by which they are carried, and a non-ionizable insulating material completely filling the spaces within said 10 folds

8. A high-voltage X-ray tube comprising an envelope having an equipotential portion, and

two end portions of insulating material sealed to the ends thereof, an anode and a cathode spaced apart within said envelope to form a voltage-drop space and each carried by one of said end portions, each of said end portions having an annular fold open to the outside of the tube, said folds extending into the vacuum space of the tube and lying outside the voltage-drop space, and a non-ionizable insulating material completely filling the spaces within said folds. 5
